UNITED STATES PATENT OFFICE.

SOCRATES A. XIPPAS, OF BUFFALO, NEW YORK.

DESIGN FOR A SIGNAL BOX.

Application filed August 11, 1928. Serial No. 27,788. Term of patent 7 years.

To all whom it may concern:

Be it known that I, SOCRATES A. XIPPAS, a citizen of the United States, residing at Buffalo, in the county of Erie and State of New York, have invented a new, original, and ornamental Design for Signal Box, of which the following is a specification, reference being had to the accompanying drawing, forming a part thereof, in which—

Fig. 1 is a front elevation;
Fig. 2 is a bottom plan view; and
Fig. 3 is a top plan view.

I claim:

The ornamental design for a signal box, as shown.

SOCRATES A. XIPPAS.
